United States Patent Office

Des. 194,702

Patented Feb. 26, 1963

194,702

HOLDER FOR NAPKINS OR THE LIKE

Rudolph C. Planeta, Portland, Conn., assignor to The Artistic Wire Products Co. of Conn., Incorporated, Taftville, Conn., a corporation of Connecticut

Filed Dec. 19, 1961, Ser. No. 67,956

Term of patent 14 years

(Cl. D44—24)

Fig. 1.

Fig. 2.

Fig. 3.

FIG. 1 is a top plan view of a holder for napkins or the like embodying my new design.

FIG. 2 is an elevation side view of said holder.

FIG. 3 is an elevation end view thereof.

I claim:

The ornamental design for a holder for napkins or the like, substantially as shown.
